Patented Sept. 5, 1916.

Inventor

Adolph Ballenberg
By his Attorney
Joseph L. Levy

UNITED STATES PATENT OFFICE.

ADOLPH BALLENBERG, OF NEW YORK, N. Y.

CASTER.

Specification of Letters Patent.

Patented Sept. 5, 1916.

1,196,835.

Application filed March 11, 1916. Serial No. 83,478.

To all whom it may concern:

Be it known that I, ADOLPH BALLENBERG, a citizen of the United States, and a resident of the city, county, and State of New York, have invented a certain new and useful Improvement in Casters, of which the following is a specification.

This invention relates to casters and the like and particularly those devices designed for use in connection with articles of furniture and other articles, and especially articles having hollow or tubular legs, to which the caster is applied, and the object of this invention is to provide a device of this character which is detachable and regulatable to the varying sizes of tubular or hollow legs and which is held in position by a clamp device which I will describe below.

Another object of my invention is to provide a caster which is at all times held securely within the caster leg to avoid dropping or falling out regardless of the varying sizes of the tubular or hollow legs and which is provided with an improved bearing for allowing a free and easy rotation of the caster at all times.

These and other improvements are provided by my invention, a more particular description of which will appear below.

Reference is to be had to the accompanying drawings, forming part hereof, in which—

Figure 1 is a side elevation partly in section of my improved caster, surrounded by a tubular leg; Fig. 2 is a rear elevation of the same; and Fig. 3 is a plan view of the same partly in section showing the caster engaging with the tubular leg.

Throughout the various views of the drawings, similar reference characters designate similar parts.

In the accompanying drawing, I have shown a yoke member 1, having side arms 2 preferably formed integral therewith, which side arms are connected together by a pintle 3, upon which is rotatively mounted the roller 4.

Above the yoke 1 is mounted a conical bearing 5 having four side ribs 6, upon which rests the lower end of the hollow or tubular leg, as will be described below. Extending downwardly from the under surface of the bearing 5 is a stud 7, which may be formed integral with the bearing, and upon which is rotatively mounted the yoke 1, a washer 8 being placed between the upper

surface of the yoke 1 and the under surface of the conical bearing 5 to minimize friction. A rod 9 extends upwardly through the stud 7 and bearing 5 and is rotatable 60 therein. The retaining clamp comprises a pair of upwardly extending side arms 10 having their lower ends 11 bent horizontally and overlapping one another, and extending toward the side arms 10. Each one of the 65 horizontal parts 11 are perforated as at 12, which perforations fit loosely over the rod 9 and allow the side arms 10 an outwardly pivoting movement, as will be described below.

The upper end of the rod 9 is screw threaded as at 13, and mounted on said threaded portion and vertically movable thereon is a conical plug 14, the upper ends 75 of the arms 10 being bent horizontally and inwardly at 15 against the side of the plug 14. A head 16 is provided upon the upper end of the rod 9 to restrict the movement of the plug 14 on the rod and prevent the same from being moved off, as will be described 80 below. A stop 17 is on the rod 9 to restrict the downward movement of the plug 14. A stop 18 is secured on the rod 9 and extending between said stop and bearing down 85 upon the parts 11 is a spring 19.

From the foregoing, the operation of my improved caster will be readily understood. A head 21 is provided on the lower end of the rod 7, which head is slotted as at 22 for the reception of a tool for turning or rotating the rod 9. The turning of the rod causes the plug 14 to move up or down, as may be desired. By causing the plug 14 to move downwardly, the tapering sides of the plug force the arms 10 outwardly and cause 90 the same to bear with force against the interior sides of the tubular or hollow leg 20, as indicated in dotted lines in Fig. 1, holding the caster firmly in the tube. It will be noted that when the side arms 10 are forced outward, this outward movement causes the parts 11 to rise upwardly against the tension 95 of the spring 19 which resiliently resists this upward movement.

It will be noted from Fig. 3, that when a tubular leg of cylindrical cross section is used, the side arms 9 bear against the sides of the leg 20 and contact therewith at four corners.

The leg 20 rests securely and firmly on the conical bearing, which because of its shape holds the leg upright and firm. By

the use of the conical bearing upon which the end of the tubular or hollow leg can rest and by the use of the expandible clamp, my improved caster can be used in connection with any size or configuration of tubular leg.

From the foregoing, it is obvious that my invention is not to be restricted to the embodiment herein shown, but is broad enough 10 to cover all structures coming within the scope of the annexed claims.

Having described my invention, what I claim is:

1. A caster or the like comprising a roller, 15 a mounting therefor, a bearing for a hollow leg, a rod extending from said bearing, a clamp having a pair of arms, means movable on the rod for causing said arms to spread outwardly and resilient means bearing on a portion of said clamp and resiliently resisting the outward spreading movement of the arms.

2. A caster or the like, comprising a roller, a mounting therefor, a conical bearing for a hollow leg, a rod extending upwardly from said bearing, a clamp having 25 a pair of arms extending upwardly from the bearing, movable means on the rod for spreading the arms outward and a spring 30 for resiliently resisting the outward movement of said arms.

3. A caster or the like having a ribbed conical bearing for a hollow leg, a rod rotatable in said bearing and extending upwardly therefrom, a clamp having a pair of side arms extending upwardly from the bearing, movable means on the rod for expanding the arms outwardly and a spring 35 contacting with a portion of said arms and resiliently resisting outward movement of the same.

4. A caster or the like having a roller, a mounting therefor, a ribbed conical bearing, a stud on said bearing on which the roller mounting is rotatively mounted, a rod 45 extending through the conical bearing and up-

wardly therefrom, arms extending upwardly from the bearing, the lower ends of said arms resting on the bearing, a spring bearing downwardly on said ends and means movable on the rod for expanding the arms outwardly.

5. A caster or the like having a roller, a mounting therefor, a ribbed conical bearing, a stud on said bearing upon which the roller 55 mounting is rotatively mounted, a rod extending through the conical bearing and upwardly therefrom, arms extending upwardly from the bearing, the lower ends of said arms being bent horizontally and resting upon the bearing, a spring bearing downwardly on said ends, and a plug movable on the rod and bearing against the upper end of the arms to cause the same to spread outwardly.

6. A caster or the like having a bearing, ribs on said bearing with their surfaces tapering inwardly toward the top of said bearing, a rod extending upwardly from said bearing, a conical plug movably mounted on said rod, a pair of arms extending upwardly at the sides of the rod, parts on said arms contacting with the movable plug and a spring exerting a downward pressure on portions of said arms at their lower ends.

7. A caster or the like having a ribbed bearing, a rod extending upwardly from said bearing, a conical plug movably mounted on said rod, a pair of side arms extending upwardly at the sides of said rod, parts on the upper ends of said arms bent inwardly to contact with the plug, parts on the lower ends of said arms extending horizontally and inwardly and overlapping one another, openings in said parts through which the rod extends, a spring surrounding the rod and exerting a downward pressure on said parts on the lower ends of the side arms.

Signed at the city, county and State of 90 New York, this 8th day of March, 1916.

ADOLPH BALLEMBERG.
